United States Patent

Des. 234,976
Patented Apr. 22, 1975

234,976

CAMERA STROBE ATTACHMENT OR THE LIKE

Sol Tiffen, 58 Midwood Cross, Roslyn, N.Y. 11576

Filed Oct. 25, 1972, Ser. No. 300,625

Term of patent 14 years

Int. Cl. D26—05

U.S. Cl. D61—1 F

FIG. 1 is a front perspective view of a camera strobe attachment showing my new design;

FIG. 2 is a left side elevational view thereof;

FIG. 3 is a bottom plan view thereof; and

FIG. 4 is a rear elevational view thereof.

I claim:

The ornamental design for a camera strobe attachment or the like, substantially as shown and described.
